 Eclipse Aviation Corporation, East Orange,
 N. J., a corporation of New Jersey

Application June 25, 1934, Serial No. 732,333

9 Claims. (Cl. 170—162)

This invention relates to propellers and more particularly to propellers of the type having a plurality of blades, the angularity or pitch of which may be varied during operation.

One of the objects of the present invention is to provide, in a variable pitch propeller, a novel pitch-limiting mechanism so constituted as to be automatically operable in accordance with the speed of rotation of the propeller to limit the reduction in pitch thereof, whereby the propeller speed may be readily limited irrespective of power, air density or other conditions to which the aircraft is subjected.

Another object of the invention is to provide, in a construction of the above character, a novel mechanism embodying a normally-circulating fluid system entirely contained within the propeller thus avoiding all fluid-sealing problems usually inherent in such mechanisms.

A further object is to provide, in a mechanism such as that indicated above and wherein a normally-circulating fluid system carried by the propeller is employed, a novel mechanism whereby the circulation of the fluid is interrupted to permit a build-up of pressure to oppose a further decrease in the pitch of the blades as soon as the speed of rotation of the propeller has attained a predetermined maximum.

A still further object is to provide, in a variable pitch propeller of the above character, a novel centrifugally-governed device for interrupting the circulation of fluid at a predetermined maximum speed of rotation of the propeller.

A further object is to provide, in a variable pitch propeller having a closed circulating fluid system functioning to limit the maximum rate of revolutions of the propeller, a novel arrangement embodying a pump in said system for circulating fluid therein together with connections between a stationary member and a propeller for operating the pump.

Other objects and novel features of the invention will appear more fully hereinafter from the following detailed description when taken in connection with the accompanying drawings, wherein one embodiment of the invention is illustrated. It is to be expressly understood, however, that the drawings are utilized for purposes of illustration only and are not designed as a definition of the limits of the invention, reference being had for this purpose to the appended claims.

In the drawings, wherein similar reference characters refer to similar parts throughout the several views:

Fig. 1 is a side view, partly in section, of a

propeller constructed in accordance with the present invention;

Fig. 2 is an enlarged sectional view of a portion of the mechanism shown in Fig. 1, and

Fig. 3 is a vertical sectional view of the propeller shown in Fig. 1.

Referring more particularly to Figs. 1 and 2, a propeller constructed in accordance with the present invention is illustrated therein as being constituted by a rotatable engine shaft or extension 10 thereof 5 and a hub 6 drivably connected thereto as by means of a driving block 7 but relatively movable longitudinally thereof in response to the thrust exerted by the blades, there being provided a plurality of bearings 8 interposed between 15 the hub and driving block for more readily enabling such movement of the hub. The latter is provided with a plurality of radially-extending sockets 9 adapted to rotatably receive the inner or root ends of propeller blades 10, there being 20 also provided suitable link mechanisms 11 interconnecting the blades with a plate member 12 fixedly secured to the propeller shaft, these last named mechanisms being effective to vary the pitch of the blades during the aforesaid thrust- 25 responsive movement of the hub relative to the shaft.

In order to yieldably oppose forward axial movement of the hub with respect to the shaft for the purpose of arresting such movement at 30 certain positions along the shaft in accordance with the degree of thrust exerted by the blades under the existing conditions of operation, there is preferably provided a plurality of resilient members, such as for example coil springs 35 13, arranged in a circle concentric with respect to the shaft and having one end thereof bearing against a plate 14 secured in any suitable manner to a forward extension 15^a of driving block 7, the other ends of said springs bearing against a 40 cylinder 15 carried by the propeller hub and being provided for a purpose which will appear more fully hereinafter. It is to be noted that when the parts are in the position shown in Fig. 1, the pitch of the blades is a maximum, the pitch being 45 gradually reduced during forward movement of the hub relative to the shaft in response to the thrust of the blades, the above mentioned resilient members 13, however, serving to yieldably oppose such movement and to arrest the hub 50 in such a position relative to the shaft that the pitch assumed by the blades will be substantially proportional to the thrust thereof and such as to yield a substantially maximum propeller efficiency for the conditions of thrust imposed.

One of the features of the present invention resides in the provision of means for limiting the maximum rate of revolutions of the propeller and such means cooperate with the pitch-changing mechanism in such a manner that at a predetermined rate of maximum revolutions, further reduction in the pitch of the blades is prevented. In the form shown, such means are fluid operated and include a normally-circulating closed fluid system. Preferably, the system is carried entirely by the propeller and includes a suitable gear pump 16 comprising driving and driven gears 17 and 18 respectively, the former being suitably driven by a stationary gear 19 meshing with an elongated pinion 20. During rotation of the propeller, the gear pump 16 pumps any suitable fluid such as oil, for example, through conduit 21 which communicates with cylinder 15 surrounding the propeller shaft. In this last named cylinder, a circular piston element 22 concentric with the propeller shaft is disposed and such element, as shown, is secured to one end of pins 23 and 24, each of these pins being secured at the other end to the plate 14. As shown more particularly in Fig. 2, a hollow screw 25 secures piston 22 to the pin 23 and the latter is provided with a passage 26 which conveys fluid from the cylinder 15 to a fluid reservoir 27 by means of conduit 28 and passages 29 and 30, there being a valvular element 31 disposed in said last named passage normally permitting flow of fluid to said reservoir.

In order to conduct fluid from the reservoir 27 back to the pump 16, a conduit 32 communicates with the reservoir through passage 33 and also communicates with a passage 34 provided in pin 24, this last named passage conducting fluid to a return conduit or duct 35 through a hollow member 36 threadedly secured at one end thereof to the pin 24 and slidably received in a suitable aperture 37 in the propeller hub.

With the above named construction, it will be readily perceived that during rotation of the propeller, the pump 16 normally circulates fluid through passage 21, cylinder 15, passage 26, conduit 28, passages 29 and 30 to the reservoir 27 and fluid from such reservoir is conducted back to the pump through 33, 32, 34, 37 and return duct 35. As long as no obstruction is offered to the flow of fluid, no pressure will be built up in the cylinder 15 sufficient to oppose relative movement between the cylinder 15 carried by the hub and piston 22 carried by the propeller shaft and change in pitch of the propeller blades may be readily effected.

Upon reduction in pitch of the blades, however, the rate of revolutions of the propeller rises and in order to limit the maximum rate of revolutions in order to secure maximum propeller and engine efficiency, a centrifugally-operable mechanism is provided for obstructing the flow of fluid in the above described system. As shown, such means comprise the valvular mechanism 31 which is slidably received in a cap 38 carried by the forward portion of the engine shaft, such valvular mechanism being normally urged to the position shown as by means of a spring 39, the compression of which may be varied by adjustment of screw 40. In the position shown, the valve 31 establishes communication between duct 35 and reservoir 27 by reason of the cut-away portion 41 but as the speed of the propeller increases, this communication is gradually cut off by outward movement of the valve 31 in response to centrifugal force. As the valve moves outwardly under these conditions, communication between the pump and res-

ervoir 27 is gradually closed off and the pump gradually builds up pressure within cylinder 15 to offer an increase in resistance to relative movement between the cylinder and piston 22 during a further decrease in the pitch of the blades. 5 This resistance gradually increases until communication between the pump and reservoir 27 is entirely shut off, at which time sufficient pressure will be built up in cylinder 15 to prevent a further decrease in the pitch of the blades. A 10 suitable by-pass valve 42 resiliently urged to its seat as by means of spring 43 serves to by-pass the fluid around the valve 31 to duct 44 in order to limit the pressure which may be built up in cylinder 15. 15

In operation, thrust-responsive movement of the hub with respect to the propeller shaft effects a reduction in the pitch of the blades through the link mechanisms 11 and during such movement of the hub, the cylinder 15 will be moved 20 to the right with respect to the stationary piston 22. The resilient means 18, as above stated, serve to resiliently oppose such thrust-responsive movement of the hub and in normal operation, the hub will move forwardly and backwardly to decrease 25 and increase the pitch of the blades in accordance with the thrust exerted thereby. The fluid system including the gear pump has a normally-circulating flow of fluid therein until such time as the valve 31 is moved in response to centrifugal force 30 to such a position as to obstruct the circulation of fluid, whereupon pressure built up in cylinder 15 by continued operation of the pump 16 will prevent any further decrease in the pitch of the blades and hence will limit the maximum rate 35 of revolutions of the propeller.

While one form of the invention has been shown and described herein, it is to be understood that the same is not limited thereto but may be embodied in other forms as well known to those 40 skilled in the art. Reference will, therefore, be had to the appended claims for a definition of the limits of the invention.

What is claimed is:

1. In a variable pitch propeller having a plurality of blades, means including a relatively movable hub and shaft for automatically varying the pitch of said blades during operation of the propeller, fluid pressure-operated means for limiting the reduction in pitch, and speed-responsive mechanism for rendering operative said fluid pressure-operated means to limit said pitch reduction. 45

2. In a variable pitch propeller having a plurality of blades, means for automatically varying the pitch of said blades during operation of the propeller, fluid pressure-operated means independent of said pitch-varying means for opposing further movement of said pitch-varying means after the pitch of the blades has reached 60 a predetermined minimum, and centrifugally-operable mechanism for effecting the operation of said fluid pressure-operated means to oppose further movement of said pitch-varying means in 65 the direction to reduce the pitch. 65

3. In a variable pitch propeller having a plurality of blades, means for automatically varying the pitch of said blades during operation of the propeller, fluid pressure-operated means independent of said pitch-varying means for opposing movement of said pitch-varying means, and mechanism operable at a predetermined speed of rotation of the propeller for effecting the operation of said fluid pressure-operated means to 70 75

- oppose further movement of said pitch-varying means in one direction.
4. In a variable pitch propeller having a plurality of blades, means for automatically varying the pitch of said blades during operation of the propeller, means independent of said pitch-varying means and operable to oppose further movement of said pitch-varying means only after the pitch of the blades has reached a predetermined minimum, and means responsive to the speed of rotation of the propeller at said predetermined minimum pitch for effecting the operation of said opposing means.
5. In a propeller of the type having a plurality of blades, and a relatively-movable hub and shaft, the pitch of the blades being automatically varied in accordance with such relative movement responsive to the thrust of said blades, the combination with said propeller, of fluid pressure-operated means for opposing the pitch-changing operation only after the pitch of the blades has reached a predetermined minimum, and centrifugally-operable mechanism for determining the initiation of operation of said fluid pressure-operated means.
6. In a variable pitch propeller having a plurality of blades, means for automatically varying the pitch of said blades during operation of the propeller, fluid pressure-operated means independent of said pitch-varying means operative for opposing a further decrease in the pitch of the blades only after a predetermined speed of rotation of the propeller has been attained, and means responsive to centrifugal force and operable at said predetermined speed for rendering operative said fluid pressure-operated means.
7. In a variable pitch propeller of the type

having a relatively-movable hub and shaft and means operable during such relative movement to vary the pitch of the propeller, a fluid pressure-operated pitch-limiting mechanism cooperating with said pitch-varying means and embodying a normally-circulating fluid system, a pump in said system, and valvular means for interrupting circulation of fluid in said system whereby said pump builds up pressure therein to oppose further change in pitch.

8. In a variable pitch propeller of the type having a relatively-movable hub and shaft and means operable during such relative movement to vary the pitch of the propeller, a fluid pressure-operated pitch-limiting mechanism cooperating with said pitch-varying means and embodying a normally-circulating fluid system for limiting the reduction in pitch of the propeller, a pump in said system, and means responsive to a predetermined speed of rotation of the propeller for interrupting circulation of fluid in said system whereby said pump builds up pressure therein to oppose a further decrease in pitch.

9. In a variable pitch propeller of the type embodying a plurality of blades and a shaft drivably connected therewith, means for automatically varying the pitch of said blades during operation of the propeller, and means for limiting the reduction in pitch of the blades comprising a normally-circulating fluid system, a pump in said system, and a centrifugally-operable valve mechanism effective at a predetermined speed of rotation of the propeller for interrupting circulation of fluid in said system whereby said pump builds up pressure therein to oppose a further reduction in pitch.
